UNITED STATES PATENT OFFICE

WILLIAM LAWSON, OF WATERBURY, CONNECTICUT, ASSIGNOR TO THE
WATERBURY CLOCK COMPANY, OF SAME PLACE.

DESIGN FOR A CLOCK-DIAL.

SPECIFICATION forming part of Design No. 18,272, dated April 24, 1888.

Application filed April 29, 1887. Serial No. 236,600 Term of patent 7 years.

To all whom it may concern:

Be it known that I, WILLIAM LAWSON, residing at Waterbury, in the county of New Haven and State of Connecticut, have invented and produced a new and original Design in Clock-Dials; and I do declare the following to be a full, clear, and exact description of the same, reference being had to the accompanying drawing, which forms a part of this specification.

The accompanying drawing is a view in front elevation of a clock provided with a dial of my design.

The leading feature of my design is the figure of a Japanese.

The dial A is of ordinary pattern so far as time-indication is concerned. The Japanese, B, here represented is gowned and belted and holds up both hands, respectively on opposite sides of the head, carrying an open fan, C, in one of them. He is standing before the footlights of a stage, D. Behind and above him

are stage draperies E E E. A series of fanciful screens, F, also located behind him, form a vista through which is seen a waterscape, G, 25 with a junk, H, and light-tower I. The Japanese is a singer, and his pose proclaims it.

I claim—

The design for a clock-dial herein shown and described, the same consisting of a clock-dial bearing the representation of a Japanese holding up both hands and carrying a fan in one hand and standing in front of a background of Japanese scenery, consisting of screens and a waterscape, showing a light-house and a junk, substantially as set forth.

In testimony whereof I have signed this specification in the presence of two subscribing witnesses.

WILLIAM LAWSON.
